James S. Eaton
ATTORNEY.

UNITED STATES PATENT OFFICE

WALTER CLYDE STEWART, OF GASTONIA, NORTH CAROLINA, ASSIGNOR TO EMANUEL FROHMAN, OF GASTONIA, NORTH CAROLINA

YARN-TENSIONING DEVICE

Application filed June 5, 1929. Serial No. 368,628.

This invention relates to a tension device for textile machinery, and more especially to winders, spoolers, and the like in which it is desired to give an adjusted tension to the thread for said purposes.

5 An object of my invention is to provide a tensioning device for thread and the yarn, in which the tension can be adjusted and in which there is eliminated the possibility of 10 lint and foreign articles lodging in the tensioning device to prevent the proper operation of the same.

Another object of my invention is to provide a tensioning device which is capable 15 of being adjusted to suit various sizes of yarn, and in which the tension can be properly adjusted, and in which there is little possibility of lint and foreign articles becoming lodged in the tensioning device, and 20 preventing the proper function of the same.

Some of the objects of my invention having been stated other objects will appear as 25 the description proceeds when taken in connection with the accompanying drawings, in which—

Figure 1 is a side elevation of a portion of a spooler frame showing my invention applied thereto;

Figure 2 is an enlarged perspective view 30 of my tensioning device, and associated parts of the machine to which it is adapted to be secured;

Figure 3 is a cross-sectional view through 35 my tensioning device and being taken along the line 3—3 in Figure 1;

Figure 4 is an end view of my tensioning device.

Referring more specifically to the drawings the numeral 10 indicates the transversely disposed shaft on which the members 11 are adjustably mounted, said members 11 being adapted to hold the bobbin loosely, said bobbin being indicated by the reference character 12 and this bobbin being mounted 45 on the arm 13 for free movement, and from this bobbin 12 the thread 14 is drawn upwardly through my tensioning device 15, which tensioning device is pivotally and adjustably mounted on the bolt 16 and the 50 upper end of the member 11, and then the

thread goes through the guide member 17 which is mounted on the rod 18 and the thread is then wound on to the spool 19 which is positively driven by means of the pulley 20 driven by the belt 21.

55 My adjusting device comprising the member 22 which is pivotally and adjustably mounted on the bolt 16 as above described, and this member 22 projects outwardly and has the curved portion 23, with the projecting portion 24 which prevents the tensioning means proper from dropping out of the division in which the same is mounted. A bolt 25 pierces the member 22 and also the member 26, which member 26 is curved as at 27 to 60 engage the tensioning device 28, which tensioning device 28 has the ball 29 mounted therein, and has the downwardly and inwardly sloping wall portions 30, in which the ball 29 is adapted to rest. These wall 70 portions 30 extend all the way through the member 28, and the thread is adapted to be passed upwardly through this passageway, and between the ball 29 and the wall portions 30. This member 28 has rounded, upward 75 and lower surfaces, and is preferably made of porcelain, and the ball 29 is preferably of chilled steel, and this ball 29 can be varied in size and weight to suit the size of the thread which is being passed through the 80 tensioning device.

This tensioning device 28 has the slot 32 cut in one side thereof with the inwardly slanting portions 33 and 34 so that the thread can be instantly passed into the tensioning 85 device, and due to the fact that it is held by the winding and spooling operation on the opposite side of the passageway than where the slot occurs, and there is no danger of the thread coming out of the slot except when removed manually by the operator.

In order to adjust the tension under which the thread is held the device may be adjusted in various positions as shown by the dotted lines in Figure 1, it being evident that as 90 the tensioning device 15 is raised upwardly in the dotted lines which is shown in Figure 1 that the tension will be decreased and the greater tension will be secured when the device is in the position as shown in full lines. 100

It is of course understood that this device can be adjusted in any desired position as to angularity with respect to the horizontal and the dotted lined position shown in Figure 1, is merely one of the adjusted positions into which this device may be placed.

I also find that I can use balls not only of different sizes made of steel in order to adjust the tension for various sizes of yarn, but I also have found that by using balls of various material such as glass, porcelain, and other materials that the tension can be regulated in this manner as well as by changing the angularity of the tensioning device with respect to the horizontal.

It is thus seen that I have provided the tensioning device in which the possibility of lint and other material lodging in the device is removed due to the fact that the ball 29 is in a constant whirling motion while the thread is being passed therethrough, and thus all lint is entirely removed from the slot, so that it is impossible for the tensioning device to become out of order on account of lint lodging therein, as occurs in many tensioning devices which has heretofore been used. It is of course evident that when a different size of ball is desired to be inserted into the device, that the member 26 is removed and this allows the member 28 to be taken out and a new ball inserted in place of the one which is in the tensioning device at the time, and then the parts are mounted back into the position as shown in the drawings and the projection 24 prevents the ball from escaping from the device regardless of the angularity at which the device is adjusted.

In the drawings and specification I have set forth a preferred embodiment of my invention, and although specific terms are employed they are used in a generic and descriptive sense only, and not for purposes of limitation, the scope of the invention being set forth in the appended claim.

I claim—

A tensioning device having a funnel shaped passageway with a ball member in said passageway, and means for adjusting the tension of thread which is adapted to be passed therethrough.

In testimony whereof I affix my signature.
WALTER CLYDE STEWART.
